MECHANISM FOR ATTACHING KNITTED FABRICS TO WOVEN FABRICS, &c.

No. 288,326.

Patented Nov. 13, 1883.

UNITED STATES PATENT OFFICE.

WILLIAM GIRLING, OF MINNEAPOLIS TOWNSHIP, HENNEPIN COUNTY, MINN.

MECHANISM FOR ATTACHING KNITTED FABRICS TO WOVEN FABRICS, &c.

SPECIFICATION forming part of Letters Patent No. 288,326, dated November 13, 1883.

Application filed April 11, 1883. (No model.)

To all whom it may concern:

Be it known that I, WILLIAM GIRLING, a citizen of the United States, and a resident of Minneapolis township, in the county of Hennepin and State of Minnesota, have invented 5 certain new and useful Improvements in Mechanism for Attaching Knitted Fabrics to Woven and other Fabrics, Leather, Felt, &c., of which the following specification is a full, clear, and 10 exact description, reference being also had to the accompanying drawings.

This invention consists in the means for attaching knitted fabrics to woven and other similar fabrics, leather, felt, &c., as herein 15 shown and described, and specifically defined by the claims.

The purpose of this invention is to attach a 20 knitted fabric of any kind to a woven or other similar fabric, leather, felt, or other similar material, especially for attaching the knitted ends to the legs and sleeves of under-clothing and to the tops of gloves, mittens, &c.; and the invention consists in the mechanical means, 25 as herein specified, for passing the loops of the last stitches made in the knitted fabric (which has been previously made by knitting-machines or by hand) through the goods to which the knitted end is to be attached, and then interlacing said projecting loops with each 30 other, and then folding one portion of the goods over the interlaced stitches and sewing or otherwise fastening to the other portion.

To insert the loops of the stitches of the 35 knitted fabric through the other fabric, I have invented the mechanism illustrated by the drawings, in which—

Figure 1 is a side view, and Fig. 2 is a plan view, of the machine by which the loops of the knitted end are passed through the fabric 40 of the garments to which they are to be attached, parts in both figures being represented as partially broken away. Figs. 3, 4, 5, 6, and 45 7 are enlarged views of one of the needles, illustrating the progressive steps in the operation of the machine. Fig. 8 is an enlarged view of a portion of the knitted end and garment to which it is attached, illustrating the manner of securing the loops. Fig. 9 is a sectional view, and Fig. 10 is a rear view, of portions 50 of the knitted end and garment, illustrating the manner of securing or finishing the

joint. Fig. 11 is a front view of the machine. Figs. 12, 13, 14, and 15 are enlarged details illustrating the construction of the needles. Fig. 16 is a perspective view of the different 55 parts of the mechanism, showing their relative positions.

A' is a frame supporting a bed or table, A², upon which the mechanism is mounted.

B' B² are two flat horizontal bars secured 60 upon the ends of the bed A², and parallel with each other. The front ends of these bars B' B² have downwardly and upwardly projecting lugs a' a², as shown, the upper lugs, a', adapted to support the forward ends of two flat horizontal bars, b' b², running back parallel with the bars B' B², and connected thereto by chocks or blocks c, the bars b' b² thus forming parallel guides or slots, in which the ends of a needle-bar, C, are adapted to be moved back and 70 forth. Small adjustable stops d' d² are arranged upon the blocks c, to project into the slots in which the needle-bar C moves, so that the throw of the bar may be regulated.

Attached to the top of the bars b' b², and also 75 to the tops of the bars B' B², are perpendicular standards D' D² D³ D⁴ D⁵ D⁶, the standards D' D² adapted to support a roller, E, between them, the standards D³ D⁴ adapted to support a rod, F, between them, and the standards D⁵ 80 D⁶ adapted to support a toothed plate, G, this arrangement forming supports for the garments to which the knitted ends are to be attached, as hereinafter shown.

The ends of the needle-bar C are connected 85 by adjustable rods e' e² to two arms, e' e², upon a rock-shaft, H'. This shaft H' is pivoted in hangers H' H² beneath the bed A², and adapted to be operated by a treadle, H⁴, connected to it by an adjustable rod, H⁵, and arm H⁶, so 90 that the motion of the treadle will throw the needle-bar back and forth.

H' H² are two other arms branching from the shaft H', and connected to a vibrating lever or arm, H⁷, pivoted at its center to the frame A' by springs H¹⁰ H¹¹, so that the treadle will be held up and the needle-bar forward, except when pushed back by the action of the treadle.

g' are the needle-heads carrying the needles 100 g², and secured to the needle-bar C, in the ordinary manner, by bolts g³, as shown. In the

drawings four needles are shown in each "head;" but this number may be increased or decreased, according to the size of the yarn or thread of the knitted ends. The needles are 5 formed with sharp points and barbs or hooks and latches g^4 , as shown in Figs. 12, 13, and 14.

P' is a flat bar having sharp edges on both sides, and connected by arms $P^2 P^3$ to the standards $D' D^2$, and adapted, when thrown down 10 in front of the needles, to catch beneath the forward point of the latches g^4 , as shown in Fig. 12, and throw them all backward at once when the needles are pushed forward, and also when thrown down in the rear of the latches, 15 as shown in Figs. 3 and 4, to close all the latches at once when the needles are drawn backward, as hereinafter shown. A spring, P^4 , holds the plate P' up out of the way when not 20 in use. The plate P' is not shown in Fig. 2.

Attached to the rear of the lugs a^2 , and running across beneath the lower line of the needle-bar C , is a bar, K' , to which is attached a series of heads, K^2 , having upright pins h , corresponding in number with and adapted to 25 pass up between the needles g^2 when the needle-bar is in its forward position, as shown in Figs. 1, 2, 11, and 16.

Attached across the face of the heads K^2 is a plate, K^4 , having outwardly and downwardly 30 projecting points i , over which the lower edge of the garment is fastened, while a toothed plate, L , is attached below the bar K' , to hold the lower end of the knitted end, as hereinafter shown.

M' is another flat bar, having pivots m on its ends, fitting into slotted frames $N' N^2$, attached to the front ends of the bars $B' B^2$, and adapted to support a series of heads, M^2 , having upright pins n , corresponding in number 40 with the pins h in the heads K^2 . The bar M' has a handle, M^3 , by which it may be moved up and down by its pivots m in the slotted frames $N' N^2$, the whole forming a holder to support the garment while being punctured 45 by the needles.

In Fig. 16 portions of the different parts of the machine are shown in perspective in their relative positions.

The operation is as follows: The bar M' is 50 dropped down into the lower ends of the frames $N' N^2$, as shown by dotted lines in Fig. 1. The bar C is pushed back far enough to allow the front edge of the plate P' to come beneath the front edges of the latches g^4 , as shown in Fig. 55 12, and then the needle-bar is brought forward, which will cause the plate P' to throw all the latches over backward, as shown in Figs. 3, 6, and 14. The plate P' is then raised 60 up and held up out of the way by the spring P^4 , as shown in Figs. 1 and 11. The needle-bar is then forced backward and held backward; and when the knitted fabric is to be attached to garments the end of one of the sleeves or legs of the garment is taken, before the seams 65 are sewed up, and laid over the roller E and passed down beneath the plate P' , and the

lower edge caught upon the pins i , projecting from the plate K^4 . The garment is then passed beneath the rod F and drawn tight and stretched over the toothed plate G . The plate 70 M' is then brought up and its pivots m dropped into sunken places m^2 in the frames $N' N^2$.

This brings the pins n up against the outer surface of the cloth of the garment, while the fixed pins h support the rear surface. The 75 two sets of pins h n are directly in line with each other, as shown in Fig. 2, so that when the needle-bar is brought forward the needles will puncture the cloth and pass between the pins, the pins serving to support the cloth 80 while being so punctured. The form of the latches, as shown in Fig. 15, is such that they readily pass through the cloth with the needles. The holding-plate M' , with its pins n , is then slipped down again, as shown by dotted lines in Fig. 1. One of the knitted ends 85 is then taken before its sides are sewed up, and each stitch of the end where the knitting stops is looped over one of the needles g^2 , behind its barbed end, as shown in Fig. 3, which 90 represents the relative positions of one of the needles and its latches, R representing the cloth of the garment, T the knitted end, and t the looped stitches. The lower end of the 95 knitted end is then drawn down and caught over the teeth on the bar L . The plate P' is then brought down, as shown in Figs. 3 and 14, so that it will catch the latches g^4 and throw them over, as shown in Fig. 4, when the needles are drawn backward. The needles are 100 then drawn backward, which will cause them to draw the loops t through the cloth, as shown in Fig. 5. The garment is then released from the bar G , rod F , and roller E , and dropped down below the needles and pushed backward 105 toward the needle-bar, which will cause the looped stitches t on the needles to throw the latches backward and pass beyond them, as shown in Fig. 6. The garment and its attached knitted end are then drawn off from the 110 needles, the loops t passing beneath the latches and closing them again, as shown in Fig. 7, and allowing the easy withdrawal of the loops from the needles. The loops t are then interlaced with each other, as shown at t' in Fig. 115 8, thereby firmly securing the knitted end to the cloth of the garment. The end R' , which projects below the loops t , is then folded over upon the inner side of the main portion of the garment and sewed fast thereto, as shown 120 in Figs. 9 and 10, and the seams of the garment and knitted end properly secured in the ordinary manner. This mechanism is adapted to attaching a knitted fabric to any quality of woven goods, cotton, flannel, silk, or to 125 leather gloves or mittens. The finer the material of which the knitted ends are made the finer and closer together the needles g^2 will be arranged.

Having described my invention, what I 130 claim is—

1. The combination of a series of latch-

- needles adapted to be passed simultaneously through a fabric or material, means for moving the said needles forward and back, a series of stationary pins, and a series of movable pins, between which pins the needles pass, and between which two series of pins the fabric or material is held, whereby the loops of a knitted fabric are drawn through the said fabric or material, substantially as described.
- 5 2. The combination of a series of latch-needles adapted to be passed simultaneously through a fabric or material, means for moving the said needles forward and back, a series of stationary pins, and a series of movable pins, between which pins the needles pass, and between which two series of pins the fabric or material is held, and means for simultaneously opening and closing the needle-latches, substantially as and for the purpose herein specified.
- 10 3. The combination of a series of needles having sharp points, barbs or hooks in the rear of said sharp points, and latches piv-
- 15 oted to said needles and adapted to cover said barbs or hooks, means for moving said series of needles in a line parallel with their lengths, a series of stationary pins between which said needles pass in their said movement, a series of movable pins adapted to be set between said needles and opposite to said fixed pins, means for holding a woven or other fabric in position with relation to said needles and pins, said needles being adapted to receive a knitted fabric over said barbs or hooks thereon, and means for supporting the free end of said knitted fabric with relation to said needles and pins, substantially as and for the purpose specified.
- 20 In testimony whereof I have hereunto set my hand in presence of two subscribing witnesses.
